UNITED STATES PATENT OFFICE.

HENRY L. MENDAL, OF BALTIMORE, MARYLAND.

WASHBOARD.

1,250,929.

Specification of Letters Patent. Patented Dec. 18, 1917.

Application filed January 3, 1917. Serial No. 140,437.

To all whom it may concern:

Be it known that I, HENRY L. MENDAL, a citizen of the United States, residing at Baltimore, in the county of Baltimore and State 5 of Maryland, have invented a new and useful Washboard, of which the following is a specification.

My invention relates to improvements in washboards whereby applying a plurality of 10 cavities at one end of the board, the same can be utilized as a compress washer. This appliance may be added to an ordinary washboard, but more particularly to a washboard made with two parts, divided in center ver- 15 tically, and provided with standards on the sides of each section, and connected by a hinged arrangement, in order to fold at will. When the boards are folded to be used as a compress washer, the standards are used as 20 handles to perform the work of raising and lowering the device.

Although by the simple device herewith disclosed there can be provided a foldable appliance, made either of wood or metal on 25 the same principle outlined in the drawings, producing the same results as specified, the main feature of the folding washboard is the reduction of the size to enable the operator to utilize the device within a small vessel 30 or bucket.

The objects of my invention, are to provide a cheap, simple, and efficient combination washboard in order to wash fabrics, and clothing of a delicate texture without rubbing; also to prevent placing the hands in 35 too hot or soapy water, and to wash all heavy or other material quickly with little labor.

I attain these objects in the following description.

40 In describing my invention in detail, reference is had to the accompanying drawings forming a part of this specification, and wherein like numerals of reference indicate corresponding parts throughout the several 45 views.

Figure (1) of drawings illustrates the device when used in the ordinary manner of washboards. Fig. (2) is a view of the reverse side of the device, also showing the 50 sectional partitions or cavities, part 4 being omitted from one of the sections. Fig. (3) represents the washboard in position when folded ready for use. Fig. (4) is a perspective view of the device looking at the bottom 55 thereof.

Corresponding and like parts are referred

to in the following description as indicated in all the views of the drawing by the same reference characters.

My combination wash board and pounder 60 comprises a pair of hingedly connected sections designated A and B. The sections being identical in construction a description of one is thought to be sufficient. The sections comprise a plurality of standards 1 having 65 the upper faces thereof extending diagonally upward. The front boards 3 are interposed between said standards adjacent the upper edges 2 having a diagonal arrangement and terminating adjacent the upper edges of the 70 said standard. Rear board 4 is provided on the upper rear portion of said standard. A base board 5 is provided with apertures 6 interposed between said standards and the front and rear board thus forming a recep- 75 tacle for soap and the like when the device is used as a wash board.

Partitions 7 are interposed between said standards having the outer edges thereof secured to the front and rear boards thus providing 80 a plurality of pockets. Rubbing plates 8 are mounted in recesses extending longitudinally of the front edges of the standard presenting the desired surface for washing.

A plurality of cross bars 9 conforming in width with that of the standard is interposed therebetween at a point slightly above the center portion forming a chamber between the rubbing plate when the board is folded. 90 A plurality of apertures 10 are provided at operative points of the standard for a purpose which will hereinafter appear.

In use as a wash board the same may be used with the sections open thus presenting 95 a double rubbing surface or if the receptacle in which the washing is to be accomplished is small the sections may be folded thus presenting a single rubbing surface. When used as a pounder as particularly set forth 100 in Fig. 4 the soap may be inserted within the receptacle formed by the cross bars when the sections are folded. It is obvious that during the pounding process the water will be poured through the openings 6 and out 105 through the apertures 10 thus agitating the water within the tub and giving the desired effect. My pounder is particularly adapted for use in connection with the washing of fine fabrics where particular care is necessi- 110 tated.

While I have herein illustrated and de-

scribed with a considerable degree of particularity constructional details of the machine embodying my invention, it is to be understood that the invention is not limited 5 to the particular form and arrangement of the several parts which may be modified within a wide range without departing from the essence of the invention, the construction shown and the description based thereon being intended to be taken in an illustrative rather than a limiting sense.

What I claim and desire to procure as Letters Patent is:

The combination of a pair of foldably connected sections comprising a plurality of

standards having notches therein, rubbing surfaces mounted on the standards, cross bars interposed between said standards, a base plate having apertures therein adjacent the upper edges of said standards, front and rear boards mounted on the upper end of said standards, partitions interposed between said standards, and the notches in the standards adapted to form holes when the standards are folded for a purpose specified. 25

HENRY L. MENDAL.
